UNITED STATES PATENT OFFICE

155,332

DESIGN FOR A CABINET LATCH

William O. Burke, Rockford, Ill., assignor to
National Lock Company, Rockford, Ill., a corporation of Delaware

Application January 24, 1947, Serial No. 136,351

Term of patent 7 years

(Cl. D50—5)

To all whom it may concern:

Be it known that I, William O. Burke, a citizen of the United States, residing at Rockford, in the county of Winnebago and State of Illinois, have invented a new, original, and ornamental Design for Cabinet Latch, of which the following is a specification, reference being had to the accompanying drawing, forming part thereof.

In the drawing:

Fig. 1 is a top plan view of a cabinet latch showing my new design;

Fig. 2 is a side elevational view of the latch shown in Fig. 1, the other side having a similar appearance; and

Figs. 3 and 4, respectively, are end elevations

looking at the handle end and the end opposite thereto.

I claim:

The ornamental design for a cabinet latch, substantially as shown.

WILLIAM O. BURKE.
